UNITED STATES PATENT OFFICE.

NOYES F. PALMER, OF JAMAICA, ASSIGNOR, BY DIRECT AND MESNE ASSIGNMENTS, OF TWO-THIRDS TO CHARLES S. GOODWIN AND HENRY R. HEATH, BOTH OF NEW YORK, N. Y.

BUTTON.

SPECIFICATION forming part of Letters Patent No. 336,061, dated February 9, 1886.

Application filed June 29, 1885. Serial No. 170,207. (No model.)

To all whom it may concern:

Be it known that I, NOYES F. PALMER, of Jamaica, Queens county, State of New York, have invented a new and Improved Button, of which the following specification is a full, clear, and exact description.

This invention relates to a button having a removable cap, so that the appearance of the button may be changed.

10 The invention consists in the elements of construction hereinafter more fully pointed out.

In the accompanying drawings, Figure 1 is a vertical central section of my improved button. Fig. 2 is a similar section of the cap; Fig. 15 3, a similar section of the head.

The letter *a* represents the head of a button, and *b* is the removable cap. The edge of cap *b* is turned down to overlap the edge of head 20 *a*. At the center the cap *b* has a threaded pin,

c, which fits into a threaded bore of head *a*. *d d* are thread or cable holes in head *a*, for attaching the button to the garment. The head *a* is convex on top, and the lower side of cap *b* is concave, as shown, to embrace the convex 25 head. The curvature of the cap *b* is, however, less than that of the head, so that while the parts meet at their edges they are separated at their faces. In this way the head *a* will not be injured by the cap *b*.

3C

I claim as my invention—

The combination of convex head *a*, having central bore and thread-holes, with the curved cap *b*, having pin *c*, the curvature of cap *b* being less than that of head *a*, substantially as 35 specified.

NOYES F. PALMER.
